UNITED STATES PATENT OFFICE

2,213,182

ELECTRIC GLOW DISCHARGE TUBE

Anton Lederer, Vienna, Austria; Catherine Danzer and General Conrad Randa, executors of said Anton Lederer, deceased, assignors, by mesne assignments, to General Electric Company, a corporation of New York

Application July 18, 1930, Serial No. 468,884. Renewed October 20, 1939. In Austria July 30, 1929

8 Claims. (Cl. 176—122)

In electric lighting tubes filled with rare gases and containing, according to whether for use on direct or on alternating current, one or two electron emitting hot electrodes (for instance glow-tubes holding heating wires), a light phenomenon appears during the discharge in the gas filling so as to form around the glowing electrodes an intense aureole while the remaining parts of the gas filling show a weaker light, diminishing with the distance from the electrodes.

Inasmuch as the lighting effect of such tubes is dependent upon the distribution of the light intensity within it, the problem was to build the tubes in such a way that as far as possible their whole and the biggest possible space selected, contributed to the lighting effect, that is to say, that there were no parts where none or hardly any lighting effect is noticeable and that on the other hand all possibilities of the discharge are made use of.

Experiments have shown, and this forms the object of the present invention, that the "full lighting" of such tubes is dependent upon the proper mutual distance and on the arrangement of the electrodes, and on the shape and dimensions of the glass bulb. However, all these conditions must be considered simultaneously in order to obtain a lighting effect from the whole and the biggest possible gas-filled space.

Experiments have shown that for a rare gas tube having a globe-shaped or similar bulb and a symmetrical arrangement of the electrodes (the electrodes lying on a middle plane at equal distance from the centre of the globe) the diameter of the globe should have a length of about three times the distance between the electrodes. The possible electrode distance depends upon the nature of the tube; it may be about 50 mm. and in this case the globe shaped bulb should have a diameter of neither more or less than about 150 mm.

The light phenomena are in their distribution dependent also upon the shape of the tube so that when a cylindrical bulb is used all other relevant conditions must be suited to it. As a matter of course, in all cases, an electrode distance should be the basis which is possible under the given conditions.

The enclosed drawing shows the light phenomenon of a tube for alternating current made according to the present invention.

The two electrodes *c* are arranged on supports and are connected to the leading-in wires. If the electrodes are sufficiently heated an arc is formed. The pressure of the rare gas and the

inter-electrode spacing are mutually small enough to provide illumination by expanded "cathodic light" whilst the positive column is effectively predominated or even suppressed.

The stem *m* carries the two electrodes. Spirals 5 passing through the electrodes *c* and connected to said electrodes at one end have their other ends transversally connected by means of a conducting bridge *f* as shown. By passing current through said spirals and heating the electrodes 10 the gas or gases contained in the tube is or are ionised, and an arc is formed; and further, around each of the electrodes there develops an aureole *a* and *a*' of intensely luminescent gas 15 whereas the surrounding space up to the dotted line *r* is filled by gases of less luminosity.

The glass bulb *b* is according to the present invention selected in such a way that it substantially encloses the whole light phenomenon.

As a matter of course, and as described, there should be in order to obtain the beautiful light effect, at least one electrode which by the action of heat can emit electrons and cause the formation of an arc.

I claim as my invention:

1. An electric illuminating lamp comprising a bulb, two closely spaced electrodes therein at least one of which is capable of emitting electrons freely when heated, the diameter of the bulb being approximately three times the distance 25 between the electrodes, a resistance member capable of heating said electrode to its electron emitting temperature, one end of which resistance member is connected to the electron emitting electrode and the other end thereof to the other 30 electrode to permit the application of a potential between said electrodes, and a rare gas filling 35 for said lamp.

2. An electric illuminating lamp for alternating current, comprising a bulb, a rare gas filling, 40 two tubular electrodes of small diameter each capable of emitting electrons freely when heated, the diameter of the bulb being approximately three times the distance between the electrodes, a resistance member enclosed in and capable of heating each electrode to its electron emitting 45 temperature, one end of each resistance member being connected to an electrode and the other ends of said members being connected together by a low resistance bridge so as to permit the heating of and the application of a potential between said electrodes.

3. An electric illuminating lamp for alternating current, comprising a globular bulb, two co-operating electrodes therein located about 50 mm. 55

- apart substantially centrally therein, each of which electrodes is capable of emitting electrons freely at relatively low temperature, members for indirectly heating said electrodes, lamp terminals permitting electric current to be supplied to said heating members and a potential to be applied between the electrodes, and a rare gas filling for said lamp, said lamp bulb having a diameter of about 150 mm.
5. An electric illuminating lamp comprising a bulb, co-operating electrodes therein at least one of which is capable of emitting electrons freely at relatively low temperature, the diameter of the bulb being approximately three times the distance 10 between the electrodes, a resistance heater for indirectly heating said electrode, lamp terminals permitting electric current to be supplied to said heating member and a potential to be applied between the electrodes, one end of said heater 15 being connected to said emitting electrode and the other end to the other electrode, and a rare gas filling for said lamp.
10. An electric illuminating lamp for alternating current comprising a bulb, two co-operating electrodes therein each of which is capable of emitting electrons freely at relatively low temperature, the diameter of the bulb being approximately three times the distance between the electrodes, a resistance heater for indirectly heating 20 each electrode, one end of each resistance heater being connected to its electrode, a low resistance bridge connecting the other ends of said resistance heaters, lamp terminals permitting electric current to be supplied to said heating member 25 and a potential to be applied between the electrodes, and a rare gas filling for said lamp.
15. An electric illuminating lamp for alternating current comprising a globular bulb, two tubular co-operating electrodes located centrally therein 30 parallel with one another, each of which electrodes is capable of emitting electrons freely at relatively low temperature, a resistance member for indirectly heating each electrode, lamp terminals permitting electric current to be supplied to said heating members and a potential to be applied between the electrodes, and a rare gas filling for said lamp, the pressure of said filling 35 and the electrode separation being such that at the electron emitting temperature of said electrodes and with an interelectrode potential approximately of the order of the ionizing potential of the rare gas no appreciable positive column can arise, and the size and shape of said lamp being such that its inner wall surface is not 40 nearer either electrode than approximately the perceptible natural boundary of its cathodic light.
20. An electric illuminating lamp for alternating current comprising a globular bulb, two tubular co-operating electrodes located centrally therein parallel with one another, the diameter of the bulb being approximately three times the distance between the electrodes, each of which electrodes is capable of emitting electrons freely at 45

5. relatively low temperature, a resistance member for indirectly heating each electrode, lamp terminals permitting electric current to be supplied to said heating members and a potential to be applied between the electrodes, and a rare gas filling for said lamp.

7. An electric illuminating lamp comprising a bulb, co-operating electrodes therein at least one of which is capable of emitting electrons freely at relatively low temperature, a resistance heater for continuously and indirectly heating said electrode, lamp terminals permitting electric current to be supplied to said heating member and a potential to be applied between the electrodes, one end of said heater being permanently connected to said emitting electrode and the other end thereof being permanently connected to the other electrode, and rare gas filling for said lamp, the size and shape of said lamp bulb being such that its inner wall surface is not nearer said electrode than approximately the perceptible natural boundary of its cathodic light.

8. An electric illuminating lamp for alternating current comprising a globular bulb, two tubular co-operating electrodes located centrally therein parallel with one another, each of which electrodes is capable of emitting electrons freely at relatively low temperature, a resistance member for indirectly heating each electrode, lamp terminals permitting electric current to be supplied to said heating members and a potential to be applied between the electrodes, and a rare gas filling for said lamp, the pressure of said filling and the electrode separation being such that at the electron emitting temperature of said electrodes and with an interelectrode potential approximately of the order of the ionizing potential of the rare gas no appreciable positive column can arise, and the size and shape of said lamp being such that its inner wall surface is not 45 nearer either electrode than approximately the perceptible natural boundary of its cathodic light.

ANTON LEDERER.
